UNITED STATES PATENT OFFICE.

JOSEPH JAMES LYNN, OF MOOSE JAW, SASKATCHEWAN, CANADA.

ADJUSTABLE FLY-SCREEN.

1,236,580.

Specification of Letters Patent. Patented Aug. 14, 1917.

Application filed April 13, 1917. Serial No. 161,839.

To all whom it may concern:

Be it known that I, JOSEPH J. LYNN, a subject of the King of Great Britain, and a resident of Moose Jaw, in the Province of Saskatchewan and Dominion of Canada, have invented a certain new and useful Improvement in Adjustable Fly-Screens, of which the following is a specification.

The present invention relates to screens 10 adapted particularly for attachment to windows and the like, for excluding flies and insects.

An object of the present invention is to provide a fly screen for attachment to windows which is of such peculiar construction as to admit of the raising and lowering of the sash of the window to any desired height, and at the same time sealing the screen in the window.

Another object of the present invention is to provide a screen which is adapted to windows varying in width and to provide the screen with improved means for securing the screen in position without the use of 25 nails, screws or other devices which must be permanently secured through the window frames.

The invention further aims at the provision of a novel construction of screen of the extensible type wherein the separate overlapping frames thereof are peculiarly interlocked and sealed together and against the window casing and the adjacent sash.

The above, and various other objects and 35 advantages of this invention will be in part described, and in part understood, from the following detailed description of the present preferred embodiment, the same being illustrated in the accompanying drawing 40 wherein:

Figure 1 is an outer side elevation of the lower portion of a window having a screen constructed according to the present invention applied thereto.

Fig. 2 is a top edge view of the screen detached from the window.

Fig. 3 is a fragmentary enlarged transverse section through the screen taken on the line 3—3 of Fig. 1, the view showing the overlapping ends of the screen frame at the tops thereof.

Fig. 4 is a similar view taken on the line 4—4 of Fig. 1, showing the bottom portions of the overlapping screen frame.

Fig. 5 is a detail sectional view taken

substantially vertically through one side of the screen, showing in side elevation the improved securing means therefor.

Fig. 6 is a similar view disclosing a modified form of securing means for the screen.

Referring to this drawing, A designates a window casing provided with a sill B, and in which are mounted in the usual manner the upper and lower sashes C and D separated by the parting strip E. The window casing A is also provided at opposite sides and adjacent to its outer edge with the blind stops F, in the usual manner.

The screen of this invention comprises a pair of frames 10 and 11 which are each 70 preferably formed of sheet metal, and which are closed in by wire meshing of suitable gage to exclude flies and ordinary insects.

The top rails of the frames 10 and 11 are each formed of an overturned strip of metal 75 adapted to engage the adjacent edge of the wire meshing therein, and the top rail of the frame 10 is reinforced at its inner side by the overturning of the metal strip against the top rail to form a reinforcing strip 12 80 which is provided at its upper edge, flush with the top of the frame 10, with a laterally turned flange 13. The flange 13 carries a flexible strip 14 which projects inwardly in substantially the plane of the flange 13, 85 and which is secured to the flange by rivets or the like, a bar 15 engaging across the free side of the flexible strip 14 to hold the latter to the flange 13. The outer side of the top rail of said frame 10 is provided 90 throughout the length of the frame with an upturned and outwardly spaced locking lip 16.

The top rail of the frame 11 is similarly 95 formed from sheet metal which is bent substantially U-shaped to receive the adjacent edge of the wire meshing therebetween, and which is reinforced at its inner side by an upturned reinforcing strip 17, the latter having upon its upper edge a downturned 100 and inwardly spaced locking tongue 18 extending throughout the length of the frame 11, and adapted to fit behind the tongue 16 and the frame 10. The tongues 16 and 18 thus interlock the top of the frames 10 and 105 11 together, and admit of the relative sliding movement of one frame upon the other. The outer side of the top rail of the frame 11 is reinforced by upturned spacing strip 19 which is provided along its upper edge 110

with a rearwardly turned flange 20 which is spaced above the top edges of the frames 10 and 11, and to which is secured a flexible strip 21 by rivets or the like, and reinforced by a bar 22 engaging across the exposed side of a flexible strip 21. The free edges of the flexible strips 14 and 21 terminate in substantially the same vertical plane and are adapted to bear against the pane of glass 10 in the sash D of the window.

As shown in Fig. 4, the frame 10 is provided with a bottom rail comprising a strip of sheet metal which is overturned upon itself, and secured against the opposite sides of the adjacent edge of the wire meshing, and which is reinforced at its inner side by a reinforcing strip 23 comprising an overturned portion of said bottom rail. The outer side of said bottom rail of the frame 10 is provided with a depending outwardly spaced tongue 24 adapted to receive therebeneath the upturned tongue 25 carried upon the lower end of the bottom rail of the frame 11. The tongue 25 is formed by the turning over of the metal from which said bottom rail of the frame 11 is formed, and the tongue 25 preferably projects upwardly and in spaced relation against the inner side of the frame 11. A reinforcing or facing strip 26 is provided by the overturning of the said bottom rail of the frame 11. The tongues 24 and 25 preferably extend throughout the entire length of the frames 10 and 11 and are adapted to hold the lower portions of the frames in interlocked relation and in various adjustments.

From Figs. 2 and 3 it will be noted that the top flanges 13 and 20 of the frames 10 and 11 respectively, are of different depths, the uppermost flange 20 being adapted to extend inwardly over the tops of both of the frames 10 and 11 while the flange 13 is relatively short and extends but a short distance inwardly from the inner frame 10. This arrangement of flanges is for the purpose of supporting the flexible strips 14 and 21 in registering relation for engagement across the outer side of the pane of glass in the window to seal the screen throughout the entire length of both of the frames 10 and 11.

As shown in Fig. 2, the flanges 14 and 20 are cut away at their outer ends to form shoulders 27 adapted to receive the parting strips E of the window casing thereagainst, the flexible strips 14 and 21 being similarly cut away to fit snugly against the inner sides of the parting strips. It will also be noted that the flexible strips 14 and 21 are provided with inclined or beveled edges 28 at opposite outer ends to lie flat against the putty or other retaining strips carried by the sash D for retaining the pane of glass therein. In this manner, the screen is sealed against the window casing, and

against the sash D placed in the casing, and the sash may be raised and lowered into various positions without disturbing the seal between the same and the screen. As the strips 14 and 21 are flexible, the lower rail of the sash may be readily raised above the screen when it is desired to remove the latter or to pass the hand or object through the window.

The frames 10 and 11 are adapted to be slid one upon the other to accommodate the width of the window casing A, and the outer side rails of the screen frames are adapted to lie flat against the outer faces of the parting strips E. To hold the screen firmly in this position, adjustable fasteners are employed, each fastener comprising an ear 29 secured by screws or the like to the outer faces of the frames 10 and 11 at the outer ends of the frames. Each ear 29 has pivoted thereto a longitudinally slotted link 30 against which slidably engages a second longitudinally slotted link 31 provided with a presser foot 32 upon its outer end. The foot 32 is relatively flat, and is adapted to engage the inner face of the adjacent blind stop F. The links 30 and 31 are secured in adjustable position by means of a clamping screw 33, including a winged nut or the like which may be readily operated by the hand. One of these fastening devices is mounted upon the outer end of each frame 10 and 11 so as to bind the opposite ends of the screen in the window casing A and against the outer side of the sash D.

In Fig. 6, a slightly modified form of fastening device for the screen is shown, the same comprising an ear 29^a secured to the outer face and adjacent each outer end of the screen, the ears 29^a being adapted to rest against the inner face of the window casing A and to be secured rigidly thereto by a screw 34 or the like. Each frame 10 and 11 is provided with an attaching ear 29^a at its outer end to firmly hold the opposite ends of the screen in place.

In use, it is only necessary to place the screen between the parting strips E and the blind stops F and to brace the screen against the parting strips E and the adjacent sash D by sliding the links 30 and 31 of the fasteners upon each other to engage the presser foot 32 against the inner sides of the blind stops F.

It is apparent that the sash D may be raised and lowered within the height of the screen without breaking the seal between the screen and the sash as the flexible strips carried by the screen provide a substantially continuous sealing element extending transversely between the screen and the sash. The sash D may therefore be closed or opened without disturbing the adjustment of the screen. By releasing the clamping devices 33 the fasteners may be readily removed

from the window casing and the screen thus collapsed and taken therefrom in a relatively short time, and without the use of tools or the like. If the modified form of 5 fastener shown in Fig. 6 is employed, it is only necessary to remove the screws 34 from the sides of the window casing and to thus collapse the screen and remove the same. The interlocking tongues at the top and bottom 10 of the frames 10 and 11 securely hold the frames together and admit of their sliding upon one another, the interlocking tongues between the frames being formed of sheet metal are relatively thin and the 15 space between the frames is thus relatively small and negligible for practical purposes.

It is of course understood that various changes and modifications may be made in the details of construction of the above-specified 20 specifically described embodiment of the invention without departing from the spirit thereof and being limited only by the scope of the following claims.

I claim:—

25 1. In a window screen, the combination of a pair of slidably connected frames arranged in overlapping relation and adapted for positioning in a window casing against the sides thereof, and sealing strips secured to 30 the upper edges of the frame and extending inwardly toward the sash of the window, said strips conforming at opposite ends to the inner opposite sides of the sash rails and adapted to project into the sash frame 35 against the pane of glass to admit the vertical adjustment of the sash without breaking the seal between the latter and the screen.

2. In a window screen, the combination of a pair of frames, interlocking tongues carried 40 upon the upper and lower rails of the frames for interlocking the frames in overlapping relation, means for binding the frames in a window casing, and a pair of overlapping flexible strips carried upon the 45 upper edges of the frames and adapted for binding engagement against an adjacent sash across the entire width of the same.

3. In a window screen, the combination of a pair of frames, interlocking tongues carried 50 upon the upper and lower rails of the frames for securing the frames in overlapping relation, said frames being adapted to fit in a window casing between the parting strips and the blind stops thereof, and binding members carried upon the frames for engagement 55 against the blind stops to bind the

frames against the parting strips and the adjacent sash.

4. In a window screen, the combination of a pair of slidably connected frames adapted 60 to fit in a window casing, a pair of overlapping flexible strips carried upon said frames for binding engagement against the adjacent sash, and adjustable fasteners carried upon the frames for binding engagement 65 in the window casing to hold the screen against the sash.

5. In a window screen, the combination of a pair of slidably connected frames adapted 70 to be fitted in a window casing, means for securing said frames in the window casing independently of the sash thereof, and flexible strips extending inwardly from the upper edges of the frames for slidable engagement with the window sash to admit of the 75 vertical adjustment thereof independently of the window screen.

6. In a window screen, the combination of a pair of slidably connected frames, expandable fastening devices carried upon the 80 outer ends of the frames for binding engagement in the opposite sides of a window casing to hold the screen therein independently of the sash, and a sealing means arranged between the frames and the adjacent sash.

7. In a window screen, the combination of a pair of sheet metal frames provided with overturned tongues upon their upper and lower edges adapted to slidably connect 90 the frames, said frames having inclosing wire mesh portions, the top rails of the frames being provided with inwardly extending overlapping flanges, and flexible strips secured to said flanges for binding engagement 95 against a sash pane to admit of the vertical adjustment thereof independently of the positioning of the screen.

8. In a window screen, the combination of a pair of sheet metal frames having overturned interlocking tongues at their upper and lower edges for slidably connecting the frames, said frames being adapted to be positioned in a window casing between the parting strips and the blind stops thereof, 100 pairs of slotted links adjustably secured in overlapping relation, one link of each pair being pivotally connected to the outer end of each frame, and presser feet carried on the free ends of the other links.

JOSEPH JAMES LYNN.
